UNITED STATES PATENT OFFICE.

THOMAS A. JANNEY, OF GARFIELD, UTAH.

FLOTATION-MACHINE.

1,342,115.

Specification of Letters Patent. Patented June 1, 1920.

Application filed January 27, 1916. Serial No. 74,561.

To all whom it may concern:

Be it known that I, THOMAS A. JANNEY, a citizen of the United States, residing at Garfield, in the county of Salt Lake and State of Utah, have invented certain new and useful Improvements in Flotation-Machines, of which the following is a specification.

This invention relates to flotation processes for concentrating ores of the general type in which a freely flowing pulp is agitated with oil, or other frothing agent, and other re-agents as circumstances demand, and in which the metalliferous part of the ore is floated and removed from the pulp while in a more quiescent condition in another part of the apparatus.

The object of the present invention is to improve the apparatus used for this purpose, an important feature being the addition of means for introducing air, or other gas, as may be found advisable, in a finely divided state into the pulp when in its more quiescent condition, after said pulp has previously been subjected to mechanical agitation and aeration. This feature effects a more complete separation of the mineral particles from the gangue than now prevails, this being due to the combined action of mechanical agitation and the subsequent application of air to the pulp. The immediate introduction of air after mechanical agitation increases the effect by adding volume to the foam or froth, and expedites, as well as improves, the entire process. Circulation of the pulp repeatedly through the separation chamber and agitation cell is provided for, thereby thoroughly removing the metalliferous particles, while an orifice of restricted size at the bottom of the separator chamber permits the heavier portion of the gangue and worthless material to be slowly discharged. Connected with the duct leading to this orifice is an upwardly extending pipe which allows the lighter portions of the gangue to escape, the upper end of said pipe being adjustable in height to regulate the level of the pulp in the separation chamber. This level is maintained between the air-charging means and the overflow lip. The overflow lip has a position below the level of the outlet of the agitation vessel, and above the level at which the air is introduced. The means for introducing air comprises an air basket or

box divided into compartments at different depths below a sloping perforated medium, which leads downwardly from the outlet of the agitation cell to the lower portion of the separating chamber. Means are provided for introducing air to the different chambers in such manner as to regulate the introduction of air into the pulp at various depths in a uniform manner.

The above and other objects will be more apparent in the following specification, when taken in connection with the drawings, and the novel elements and combinations thereof will be set forth in the appended claims.

In the accompanying drawings—

Figure 1 is a cross section of the apparatus through an agitating cell and adjacent separating chambers at either side thereof.

Fig. 2 is a plan view of one of said agitating cells and adjacent separating chambers, together with portions of other cells and chambers in a series. Fig. 2^a is a sectional view showing the openings in the agitating cell for connection with the pipes 32 and 33.

Fig. 3 is a plan view of one of the air baskets, or air-introducing boxes, which have sloping positions in the separating chambers.

Fig. 4 is a cross section thereof, taken substantially on the line 4—4 of Fig. 3.

Fig. 5 is a detail view of a portion of a perforated sheet forming a part of the perforated medium of said air basket.

Fig. 6 is a detail sectional view of the structure of the air basket, taken on the line 6—6 of Fig. 3.

Fig. 7 is another detail sectional view of said structure, taken on the line 7—7 of Fig. 3.

Fig. 8 is a plan view of another of said air baskets.

Fig. 9 is a sectional view thereof, taken on the line 9—9 of Fig. 8.

Fig. 10 is a detail sectional view of the outlet to the separating chamber, showing more particularly the structural details of the restricted orifice therefor.

Fig. 11 is a sectional view of a modified form; and

Fig. 12 is a plan view of the same, partly in section.

I will refer more particularly in the earlier part of the following specification

to Figs. 1 and 2, which show the general arrangement of all of the essential elements of my invention. It will be understood that this shows but one specific form and arrangement of parts, and that it is apparent that wide variations may be made therefrom without departing from the invention as defined in the appended claims.

The agitating chamber 15 is preferably 10 cylindrical in form, with an open upper end forming a discharge outlet. A rotary shaft 19, axially disposed in said chamber, carries agitators or impellers 17 and 18 fixed thereon, the lower one—17—having vanes or 15 arms 17^a with inclined upper surfaces, said arms being of such length as to rotate within inwardly projecting ribs 27 on the inner wall of said chamber. The upper agitator 18 is similar to the agitator 17, except that its arms are longer and reach nearly to the inner surface of the cell 15. The arms of the agitator 18 pass over the upper ends of the ribs 27, and beat air into 20 the pulp that is elevated between the ribs 25 by the agitator 17. The level of the pulp in the cell in a quiescent condition is preferably maintained substantially at or below the upper ends of the ribs. The agitator shaft 19 is secured at 20—preferably by 30 screw threads—to the lower end of the shaft of a vertically disposed motor 21.

Immediately above the open end of the cell 15, with an annular space 22^a between, is a cap 22 having a downwardly-turned flange 22^b, which terminates above the separator chambers 16 and is adapted to throw the pulp elevated in said cell downwardly into 35 said chambers. The cell is preferably cylindrical in form, and is disposed within a rectangular box 23 supported by a pedestal 23^a. This rectangular box, in turn, is placed between long frame members or walls 23^b, which extend through a series of agitating and separating elements, as indicated in 40 Fig. 2. Extending laterally from these frame members are other frame members or partitions 23^c separating the adjacent separation chambers. Other wall and frame members 23^d on the outer limits of the 45 separating chambers complete the inclosure of said chambers, which receive the pulp from the agitation cells.

A launder 25 discharges the pulp into a funnel 26 leading through a suitable pipe 55 26^a to the lower portion of the agitation cell. This pipe is preferably disposed within one of the separating chambers, as shown in Fig. 1.

Within the separation chambers—one of 60 which is disposed on each side of the agitation cell—are disposed inclined air baskets or boxes 44, having their upper ends in contact with walls 23^b a suitable distance below the discharge portions 24 of the caps 65 controlling the flow from the agitation cell.

These air baskets, with perforated tops for the admission of air as will be later described, slope downwardly at such an angle as to cause the migration of the solid portions of the pulp slowly toward the lower- 70 most portions of the chamber.

Overflow lips 30 are attached to the outer walls 23^d, being composed of inclined boards 30^a, as shown in Fig. 1. The upper of said boards inclines downwardly at a 75 small angle and discharges the overflowing froth into a launder 31 running longitudinally of the series of machines. One of said launders is disposed at either side of said series, as shown in Figs. 1 and 2, and 80 carries the froth to the desired locality for further treatment.

Below the air baskets 44 in the separation chambers are circulation ducts or pipes 85 32 and 33 leading from the lowermost portions of said chambers to the lower portion of the agitation cell 15. These pipes are of large capacity, and their purpose is to allow a free return of the pulp in said chambers to the cell. The innermost ends 34 and 35 90 of these pipes terminate in front of orifices 34^a and 35^a in the agitation cell. These orifices are disposed in such relation to the ribs 27 in said cell as to prevent interference of the ribs with the inflow of the cur- 95 rent.

In the lowermost portions of the separation chambers are disposed outlets 36 leading to ordinary T-pipe fittings 37, in the lower part of which are placed reducing 100 plugs 40, which, in turn, hold porcelain bushings 38, in which is an outlet orifice of relatively small size. The bottom 36^a of said chamber is preferably made of cement or concrete, and slopes uniformly toward 105 the outlets 36. The bushings 38 are held in place by the flange 39, and may be easily replaced by bushings of other sizes, having orifices of just such dimensions as will restrict the outflow of the heavier portions of 110 the gangue to the desired slow rate. The rate of outflow can thus be regulated to cause the pulp to flow repeatedly through the pipes 32 and 33 back to the agitation cell for repeated operations upon it a sufficient number of times to insure thorough removal of the metalliferous particles by the apparatus.

The heavier portions of the gangue will slowly pass out through the bushing 38 into 115 the tailing launder 38^a, while the lighter portions of said gangue will rise in the pipe 41 and overflow at the upper end into the inclined launder 42 which leads to the tailing launder. Upon the upper end of 120 the pipe 41 is a threaded sleeve or coupling 43, by which the level of the pulp in the separation chamber may be regulated. This sleeve may be raised or lowered on the pipe 43 by rotating it. The pipe 41 is of suffi- 125 130

cient size to give an unrestricted outlet to the pulp and to take care of all pulp which enters through the launder.

Returning to the air baskets or boxes 44, it will be seen that they comprise separate air chambers 45, 46, and 47, above which are disposed the perforated sheets or plates 48, with relatively large perforations for supporting the porous sheet or membrane 49 with relatively small perforations or pores. Separate air pipes 50, 51, and 52 lead to the respective chambers 45, 46, and 47, each of said pipes being supplied with a regulating valve, as shown at 55, 56, and 57. These pipes lead to headers 53, which, in turn, receive their supply of air from the mains 54. By means of these valves the air in the chambers 45, 46, and 47 may be regulated to produce the desired uniformity 20 of flow through the different depths of pulp above said chambers.

The structure of the air baskets comprises a rectangular box formed by a bottom 58 and outer walls 59 rising thereabove. The chambers 45, 46, and 47 are separated by partitions 60 and 61. Other ribs 62 at right angles to said partitions are disposed at regular intervals for giving the necessary rigidity to the structure. To these ribs and partitions, as well as to the outer walls 59, are secured the perforated sheets 48 and porous membrane 49 by suitable strips 63 placed above them, and held in place by the bolts 64. The longitudinal strips 63^a are 35 preferably rounded at their upper edges to permit the pulp to migrate more freely over their upper surfaces. The transverse strips 63^b need not necessarily be so rounded. In the lower portions of the ribs 62 are 40 placed openings 65 for allowing equalization of the air in the different portions of each of the chambers, but no such openings are provided in the partitions 60 and 61 between the chambers themselves. One of the 45 air baskets 44 is provided with a notch 66 to prevent interference with the inlet pipe 26^a leading to the agitation cell.

In the use and operation of the present invention it will be seen that the ore pulp is 50 supplied to the machine through the launder 25, funnel 26, and pipe 26^a to the lower portion of the agitation cell 15. The motor 21 rotates the agitators 17 and 18, the centrifugal force imparted to the pulp causing it to 55 rise between the ribs 27, and causing the upper agitator 18 to beat air into the rising pulp and impel it upwardly and over the open ends of the cell under the cap 23, and downwardly into the separation chambers 60 16. The air admitted into the pulp in said chambers through the porous membranes of the air boxes 44 rises through said pulp and selects the metalliferous particles therefrom, adding to the froth formed by the agitation 65 in the cell 15. The agitator in the cell pro-

duces a large amount of froth, which flows over into the separation chambers and floats on the pulp therein, its volume being increased and the separating effect augmented by the air rising from the air baskets. The 70 accumulation of froth causes it to flow over the lip 30 and downwardly into the launder 31. The heavier particles of the pulp migrate slowly downwardly over the porous membrane of the air basket 44, and finally 75 drop over the lower edge of said air basket and downwardly toward the outlet orifice 36. A large portion of said pulp, however, cannot find an outlet, due to the restricted size of the bushing 38, and the arbitrary 80 adjustment of sleeve 43, and returns through the pipes 32 and 33 to the lower portion of the agitation cell. The circulation thus produced through the agitation cell and separation chamber causes repeated operations to 85 be performed upon the same pulp. Finally, the very heaviest particles slowly pass out through the bushing 38, while those of lighter weight ascend in the pipe 41, and escape over the upper end of the sleeve 43. 90 By means of the adjustable sleeve 43 the precise level of the pulp in the chambers can be regulated.

In Figs. 11 and 12 are shown a modified form of my improved concentrating apparatus. The air basket 67 in this form is made with a body of cast metal, with a number of compartments to receive the air below the perforated medium. This cast metal body is indicated at 67, and rests at 95 its lower edge upon a cleat or rib 68^a rigidly secured to the settling box or well 69 in the lowermost portion of the separation chamber. At its upper edge it rests upon a similar cleat 95^a, secured to the inner wall 75^a 100 between the separation chamber and agitation cell. Leading from this well back to the agitation cell 75 are the pipes 70 and 71, said pipes being secured at one end to the wall 68 of the well, and at their other ends 105 to the wall 75^a. Openings through the cell casing at 75^b lead the pulp to other openings 73 and 74 in the cell lining. The agitation of the pulp in the cell, and circulation there- 110 of from the cell to the separation chamber 115 and back through the pipes 70 and 71, is substantially the same as that previously described in connection with Figs. 1 and 2.

In the lowermost part of the well 69 is the outlet 76, leading to the fitting 77, above 120 which rises in a vertical direction the secondary overflow pipe 78. This pipe is adjusted in the fitting 77 to regulate the level of the pulp in the separation chamber. In the lower part of the fitting is the plug or 125 bushing 79, containing a small aperture similar to that described in Figs. 1 and 2.

The outlet at 79^a opens into the launder 80. The overflow from the secondary outlet 78 passes into the vertical chute or 130

launder 82, and thence into the launder 80. The overflow lip 81 allows the froth to pass outwardly into the concentrate launder 81^a. Above this lip, adjacent the box 82, is a V-shaped weir or apron 81^b to divide the current of froth and prevent it collecting in front of said launder 82.

10 A draining plug 83 is provided for cleaning the fitting 77, and other parts of the apparatus. This plug may have the form commonly known as a molasses gate.

15 A funnel 84 is provided for receiving the pulp which is supplied to the apparatus, this funnel being secured to the thickened portion 86 of the air basket body casting. An elbow fitting 85 is also secured to said casting, and forms a continuation of the inlet funnel leading to the lower part of the agitation cell. Within the agitation cell are 20 the rotary agitators 87 and 88, similar to those previously described, these agitators being secured to the upright shaft 89, which is driven by the motor 90.

25 The air chambers are supplied with air through flexible tubes or hose 91, each of which is provided with a controlling valve 94. Air is supplied to said valves from a header 92, which, in turn, is connected with the main 93.

30 The operation of this modified form is in all essential respects similar to that described in connection with the previous form illustrated in Figs. 1 to 10, inclusive.

In the form shown in Figs. 1 to 10, inclusive, the tailings in launder 38^a may be led back to the next agitation cell in the series for retreatment, and so on until the pulp is finally discharged from the last unit in the series. In like manner the tailings in launder 80, Figs. 11 and 12, may be led through a number of units in a series.

35 While I have described my invention with more or less minuteness, and as being embodied in certain precise forms, yet it will be understood that I do not desire to limit myself thereto unduly, or any more than is pointed out in the claims. On the contrary, I contemplate all proper changes in form, construction, and arrangement, the omission 45 of immaterial parts, and the substitution of equivalents, as circumstances may suggest or necessity render expedient.

I claim:-

1. The combination in flotation apparatus 55 for ore pulp, of an agitation vessel and a separating box located relatively close together and communicating directly with each other, means for mechanically agitating the pulp in said vessel to mingle air therewith 60 and propel the pulp into said separating box, and stationary means for distributing air in a finely divided condition into the substantially quiescent pulp in said separating box.

2. In a device of the class described, an agitation vessel for ore pulp contained there-

in, a separating box communicating with said vessel through upper and lower ports, agitating and impelling means in said vessel for agitating the ore pulp and for causing a circulation of said pulp from said vessel to 70 said box through the upper port and back to the vessel through the lower port, and means for introducing air in a finely divided condition into the ore pulp in said separating box.

3. In a device of the class described, a 75 froth separating box having inlet and outlet openings at the upper and lower parts thereof respectively, means for mechanically agitating ore pulp in contact with air and for supplying said pulp through said inlet opening into said separating box, an air supply chamber having a permeable wall below the level of the pulp in said box, and means for supplying air through said permeable wall to maintain an upward current of air bubbles through said pulp while said pulp is in a substantially quiescent condition.

4. In a device of the class described, an agitation vessel, a separating box communicating directly with said agitation vessel 90 through an upper port, means for agitating ore pulp in said vessel to mingle air therewith and for supplying pulp through said upper port into said separating box, and means for subjecting said pulp to the action 95 of an uprising current of air bubbles in said separating box.

5. In a device of the class described, an agitation vessel for ore pulp contained therein, a separating box communicating with said vessel through upper and lower ports, agitating and impelling means in said vessel for agitating the ore pulp and for causing a circulation of said pulp from said vessel to 100 said box through the upper port and back to said vessel through the lower port, means for introducing air in a finely divided condition into the ore pulp in said separating box, said box having an overflow lip below the level of said upper port, an outlet having a capacity less than the supply of pulp to said apparatus, and a second pulp outlet above said first-named outlet for regulating the level of the pulp in said box.

6. In a concentrating apparatus, an agitation vessel and separating box communicating with each other through two ports, means for feeding pulp to said apparatus and for discharging the same therefrom, means for agitating said pulp and for impelling it from said agitation vessel to said separating box at a more rapid rate than the pulp is fed to and discharged from said apparatus, thereby setting up a local circulation of pulp through said vessel, box, and 115 connecting ports, and means for introducing air in a finely divided condition into the ore pulp in said separating box.

7. In a concentrating apparatus, a mixing vessel and a separating box having communi- 130

cating ports at points adjacent the top and bottom thereof, a rotary agitator in said vessel adapted by centrifugal force to elevate and mingle air with an ore pulp contained therein and thereby to cause said pulp to flow into said separating box through the upper port, and means for introducing air in a finely divided condition into the pulp in said separating box.

10 8. In a concentrating apparatus, a mixing vessel and a separating box having communicating ports at points adjacent the top and bottom thereof, a rotary agitator in said vessel adapted by centrifugal force to elevate an ore pulp contained therein and thereby to cause said pulp to flow into said separating box through the upper port, and means for introducing air in a finely divided condition into the pulp in said separating box, said separating box having an overflow lip below the level of the port at the top of said vessel.

25 said vessel.

9. In a concentrating apparatus, a mixing vessel and a separating box having communicating ports at points adjacent the top and bottom thereof, a rotary agitator in said vessel adapted by centrifugal force to elevate an ore pulp contained therein and thereby to cause said pulp to flow into said separating box through the upper port, and means for introducing air in a finely divided condition into the pulp in said separating box, said box having a discharge outlet in its lower portion of a capacity less than that of the agitator, thereby causing a flow through said lower port.

30

35

through said lower port.

10. In a device of the class described, an agitation vessel for ore pulp contained therein, a separating box communicating with said vessel through upper and lower ports, 40 agitating and impelling means in said vessel for agitating the ore pulp and for causing a circulation of said pulp from said vessel to said box through the upper port and back to said vessel through the lower port, and 45 means for introducing air in a finely divided condition into the ore pulp in said separating box, said box having an outlet in its lower portion of a capacity less than said upper port.

50

11. In a device of the class described, an agitation vessel for ore pulp contained therein, a separating box located adjacent said agitation vessel, means for agitating said ore pulp in said vessel and mingling air therewith and for discharging said pulp over the upper end of said vessel, means for receiving the pulp discharged over the upper end of said vessel and conveying the same into the upper part of said separating box, a permeable medium located in said separating box and inclined downwardly from the point where said pulp enters said box, means for supplying air through said permeable medium, and means extending be-

neath said permeable medium for conveying a portion of the pulp discharged into said box back into the lower part of said agitation vessel.

12. In a concentrating apparatus, an agitation vessel and separating box having communication with each other at the upper and lower parts thereof, means in said vessel for agitating an ore pulp in contact with air and moving it in a circuit through said vessel and said box, whereby it is subjected to alternate periods of agitation in said vessel and of substantial quiescence in said box, and means for introducing air in a finely divided condition into the pulp in said box. 80

13. In a concentrating apparatus, an agitation vessel and separating box having communication with each other, means in said vessel for agitating an ore pulp in contact with air and causing a circulation of said pulp through said vessel and box, and means for introducing air in a finely divided condition into the pulp in said box, said means comprising a perforated medium having an inclined position in said box leading downwardly from that part of said box below the outlet from said vessel. 85 90

14. In a concentrating apparatus, an agitation vessel and separating box having communication with each other, means in 95 said vessel for agitating an ore pulp in contact with air and causing a circulation of said pulp through said vessel and box, means for introducing air in a finely divided condition into the pulp in said box, said means comprising a perforated medium having an inclined position in said box leading downwardly from that part of said box below the outlet from said vessel, said air-introducing means being divided into independent portions at different depths, and means for controlling the air supply to each of 100 said portions.

15. In a concentrating apparatus, an agitation vessel and separating box having communication with each other, means in said vessel for agitating an ore pulp in contact with air and causing a circulation of said pulp through said vessel and box, means for introducing air in a finely divided condition into the pulp in said box, said means comprising a perforated medium having an inclined position in said box leading downwardly from that part of said box below the outlet from said vessel, said box having an outlet below said air-introducing means of a capacity less than the circulating capacity of said agitating means, and a second outlet of unrestricted capacity above said air-introducing means.

16. In a device of the class described, an agitation vessel, and a separating box having communication with each other through upper and lower ports, a mechanical agitator in said vessel for agitating ore pulp in 130

contact with air and moving it in a circuit through said vessel and said box and said communicating ports, whereby it is subjected to alternate periods of agitation in said vessel and of substantial quiescence in said box, and means for introducing air in a finely divided condition into the pulp in said box.

17. In a concentrating apparatus, a separating box, means for introducing air in a finely divided condition into the ore pulp in said box, means for supplying a stream of pulp to said box, said box having an outlet of smaller capacity than said supplying means and said outlet being below the level of the air-introducing means, and a second outlet of unrestricted capacity leading from a point below to a point above the level of said air-introducing means, said second outlet being adjustable in height.

18. In a concentrating apparatus, a separating box, means for introducing air in a finely divided condition into the ore pulp in said box, means for supplying a stream of pulp to said box, said box having an outlet of smaller capacity than the supplying means and said outlet being below the level of the air-introducing means, a second outlet of unrestricted capacity above the level of the air-introducing means, said second outlet being adjustable in height, and an overflow lip above the level of said second outlet.

19. In a flotation apparatus, the combination of an upright conduit provided with means for admitting ore pulp at its lower portion and having an overflow at its upper portion; a perforated medium adapted to receive said overflow; means for mechanically agitating the ore pulp within said conduit and discharging it with a swirling motion upon said perforated medium; and means for forcing air through said perforated medium and into the pulp thereon, substantially as set forth.

20. In a device of the class described, an agitation vessel for ore pulp contained therein, a separating box communicating directly with said vessel through upper and lower ports, agitating and impelling means in said vessel for agitating the ore pulp and for causing a circulation of said pulp from said vessel to said box through the upper port and back to the vessel through the lower port, and means for introducing air in a finely divided condition into the ore pulp in said separating box.

21. In a concentrating apparatus, an agitation vessel and separating box communicating directly with each other through two ports, means for feeding pulp to said apparatus and for discharging the same therefrom, means for agitating said pulp and for impelling it from said agitation vessel to said separating box at a more rapid rate

that the pulp is fed to and discharged from said apparatus, thereby setting up a local circulation of pulp through said vessel, box, and connecting ports, and means for introducing air in a finely divided condition into the ore pulp in said separating box.

22. In a concentrating apparatus, a mixing vessel and a separating box having directly communicating ports at points adjacent the top and bottom thereof, a rotary agitator in said vessel adapted by centrifugal force to elevate an ore pulp contained therein and thereby to cause said pulp to flow into said separating box through the upper port, and means for introducing air in a finely divided condition into the pulp in said separating box.

23. In a concentrating apparatus, an agitation vessel and separating box having direct communication with each other at the upper and lower parts thereof, means in said vessel for agitating an ore pulp in contact with air and moving it in a circuit through said vessel and said box, whereby it is subjected to alternate periods of agitation in said vessel and of substantial quiescence in said box, and means for introducing air in a finely divided condition into the pulp in said box.

24. In a concentrating apparatus, an agitation vessel and separating box having direct communication with each other, means in said vessel for agitating an ore pulp in contact with air and causing a circulation of said pulp through said vessel and box, and means for introducing air in a finely divided condition into the pulp in said box, said means comprising a perforated medium having an inclined position in said box leading downwardly from that part of said box below the outlet from said vessel.

25. The combination in flotation apparatus for ore pulp, of an upright agitation vessel open at its upper end, a separating box located adjacent to and at one side of said vessel, a rotary agitator in said vessel adapted to mingle air with pulp, means for conveying the overflow from the upper end of said vessel directly to said separating box, and means for introducing air in a finely divided condition into the substantially quiescent pulp in said separating box.

26. The combination in flotation apparatus for ore pulp, of an agitation vessel and a separating box formed as a unitary structure, a rotary agitator in said vessel for beating air into said pulp, a communicating port through which the contents of said vessel pass to said separating box, and means for introducing air in a finely divided condition into the pulp in said separating box.

27. The combination in flotation apparatus for ore pulp, of an agitation vessel and a separating box formed as a unitary structure, a rotary agitator in said vessel for

beating air into said pulp, a communicating port through which the contents of said vessel pass to said separating box, means for introducing air in a finely divided condition into the pulp in said separating box, and means for conveying a portion of the pulp from said separating box back to said agitation vessel.

28. The combination in flotation apparatus for ore pulp, of an upright agitation vessel and a separating box mounted adjacent each other and communicating directly through an upper port, a vertical shaft mounted in said vessel, agitating blades carried by said shaft, means for introducing

pulp into the lower part of said vessel, a porous medium mounted in said separating box and inclining downwardly from said upper port, means for introducing air through said porous medium, and means for operating said shaft and thereby agitating said pulp and mingling air therewith in said vessel and impelling said pulp through said upper port into said separating box.

In testimony whereof, I have subscribed my name.

THOMAS A. JANNEY.
